UNITED STATES PATENT OFFICE.

CARL PERDELWITZ, OF BERLIN, GERMANY.

FERRULE.

SPECIFICATION forming part of Letters Patent No. 703,457, dated July 1, 1902.

Application filed November 8, 1900. Serial No. 35,885. (No model.)

To all whom it may concern:

Be it known that I, CARL PERDELWITZ, merchant, a citizen of the Kingdom of Prussia, residing at Berlin, Germany, have invented 5 certain new and useful Improvements in Ferrules for Canes and Umbrellas, (for which I have received a gebrauchsmuster in Germany, No. 135,920, dated April 10, 1900,) of which the following is a clear specification.

10 My invention relates to a ferrule for canes and umbrellas, the object being to greatly deaden the noise of canes made of metal tube or hard heavy wood when striking against the stone pavement. A further advantage 15 of my invention is that the disagreeable shock felt in the wrist when striking against hard soil is completely neutralized by the ferrule. The bolt arranged inside the ferrule is exchangeable.

20 The advantages mentioned above permit of constructing canes and umbrellas of one single metal tube. Hitherto there was little desire for canes of this kind on account of the disagreeable noise caused by the metal 25 cane when striking against hard soil.

Referring to the drawings, Figure 1 shows a vertical section of a cane made of drawn metal tube. Fig. 2 shows a vertical section of the ferrule. Fig. 3 shows a horizontal section of the ferrule. Fig. 4 shows a section of the ferrule as applied to common wooden canes.

At the lower end, Fig. 2, of the metal-tube cane at a' there is a stricture, against which 35 presses a plate b , consisting of wood or metal. e represents an elastic stopper of india-rubber or leather; c , the bolt, consisting of hard or highly-resistant metal. The bolt inside the tube is inclosed in a casing or ring f , made 40 of india-rubber, being thus firmly pressed into the said tube, so that it cannot fall out. Into the lower end of the cane the metal ring g is inserted, which serves as a reinforcement-piece of the turned end of the tube.

In Fig. 4 the metal tube is replaced by a 45 wooden stick, and the bolt differs somewhat in shape from that represented in Fig. 2, allowance having been made for the greater diameter of the wooden sticks. Here the elastic stopper e is pressed directly against the 50 wooden stick, the case of the ferrule inclosing the india-rubber parts being connected with the cane by means of a pin or screw.

Since the bolt is insulated by means of an elastic covering, it can move spring-like, and 55 thus catch the shocks in such a way as to weaken the sound and effectually prevent the transmission of the shock to the wrist of the person using the cane. The bolt, which is subject to wear, can easily be removed and 60 replaced by a new one.

Modifications in the shape of the single parts, inasmuch as they have the same effect, do not affect the invention.

Having thus fully described my invention, 65 what I claim as my invention, and desire to secure by Letters Patent of the United States, is—

1. In combination, with a cane or umbrella made of metal tube, a ferrule, comprising an 70 elastic stopper e , pressed into the said cane or umbrella, an elastic casing or ring f , a bolt c , consisting of hard or highly-resistant metal and a metal ring g , substantially for the purpose as described. 75

2. In combination with a cane or umbrella stick of wood, a ferrule, comprising an elastic stopper e , an elastic casing or ring f , a bolt c , consisting of hard or highly-resistant metal and a metal ring g , substantially for the purpose as described. 80

In witness whereof I have hereunto set my hand in presence of two witnesses.

CARL PERDELWITZ.
